ATTORNEYS

UNITED STATES PATENT OFFICE.

OTTO H. STOLBERG, OF SAN FRANCISCO, CALIFORNIA.

PERMUTATION LOCK.

Application filed November 29, 1920. Serial No. 426,939.

To all whom it may concern:

Be it known that I, OTTO H. STOLBERG, a citizen of the United States, and a resident of the city and county of San Francisco, and 5 State of California, have invented certain new and useful Improvements in Permutation Locks, whereof the following is a specification.

This invention relates to permutation 10 locks, and is designed as an improvement on the same subject matter as my former application, filed February 20, 1920, Serial No. 360,156, for lock casings.

The invention may be best understood 15 from a study of the accompanying one sheet of drawing and the subjoined description thereof. In the drawing I have shown so much of a lock of the automobile type as is necessary to an understanding of the invention 20 illustrated by it.

Figure 1 is a face view of the dial of the lock.

Figure 2 is a plan of the inner dial plate or permutation plate, as it would appear if 25 viewed from the line 2, 2, of Figure 3, looking in the direction of the arrow.

Figure 3 is a section taken on the line 3, 3, of Figure 1.

Figure 4 is a sectional view, on the line 30 3, 3, of Figure 1, showing on a larger scale, the push button 7 and its train of stem sections in the same position as in Figure 3, that is with the ignition handle in its off position and locked, all the parts being in 35 section.

Figure 5 is a similar view to Figure 4, but with the ignition handle away from its off position, and the flange plate partly oscillated thereby.

40 Figure 6 is a similar view to Figure 3, but on a larger scale, showing the push button 7 in its normal position locking the ignition handle, and a spring immediately under the button to return it to that position.

45 In the figures:—The front plate 1, the middle plate 2, and the back plate 3 are secured together by bolts 4, and are spaced apart for a purpose which will presently appear, by thimbles 5, which may be sleeved 50 on the bolts 4, as shown in Figure 3.

The front plate 1 is the dial of the lock, and is perforated by a series of holes in which are fitted push buttons 6, 7, etc., in any desired number, though I have thought 55 it necessary to mark only two with letters of reference. The plate 1 is also perforated

by a preferably central hole, in which is fitted the ignition shaft 8, operated by the ignition handle 9. Both plates 2 and 3 are also perforated in register with the perforation in plate 1. At its inner end the shaft 8, which extends through all three plates, may have an arm 10, or other device controlled by it, for opening and closing the ignition circuit, or for such other purpose 60 as the lock is used for. The ignition shaft 8 may be hollowed and through it extend a shaft 11 for controlling the lights, or for other purpose.

The push buttons are each of them provided with a flange 12, to limit their projection from the plate 1, by engaging the inner side of it, and the point to which they may be pushed back is limited by the plate 2. Projecting inward from the back of 75 each push button is a stub stem 13, long enough to project into the plate 2, and be guided thereby. Within the plate 2 and in line with stubs 13 are other stem sections 14 of a length to reach the inner side of plate 2, when the button, as 7, is pushed to its inner limit. Against the inner end of stem section 14 is a ball 15 and against the ball 15 is another stem section 16, which bears against a spring 17, which spring 17 bears, 80 at its opposite end against a stop 18. The stop may be in the form of a set screw secured to plate 3, as shown particularly in Figures 4 and 5 and which may be removed, and the spring and several stem sections including the ball, taken out to replace them 85 or change the combination. Upon ignition shaft 8 is a flange plate or disc 19, between the plates 2 and 3. The disc 19 is perforated in register with the perforations in 90 plates 2 and 3.

The operation of the mechanism is as follows:—

A spacing block 20 may be inserted between stub 13 and stem section 14 in connection with any of the buttons, as seen in connection with button 6 Figure 3, and thus cause stem section 14 to reach disc 19. In this position no resistance is offered thereby to the oscillation or rotation of the disc, unless the button be pushed, in which case stem section 14 will enter the disc, and prevent its movement. The ends of the stem sections, 14 and 16, are preferably rounded to ensure easy movement of plate 19 across 105 them. If block 20 be omitted, as seen in connection with button 7, Figure 3, then 110

stem section 16 projects into the disc and prevents its rotation until the button is pressed, when ball 15 will fill the space in the disc, and the disc may be oscillated. 5 The disc is oscillated by ignition handle 9, and locked by the projection of any stem section into it.

Thus if any number of buttons be provided with blocks as 20, it will be necessary 10 to press in all the other buttons before the disc can be moved, and the ignition handle oscillated.

Only the push buttons unprovided with blocks 20 are to be pressed in to release the 15 ignition handle, and they must all be in as far as they will go to unlock the handle. If any one of them be overlooked, or any of those buttons which have the blocks 20, be pushed, the handle will remain locked. 20 Upon releasing a button, it is returned to its normal position, by spring 17, when the handle 9 is in "off" position, and by spring 21, if the handle is away from "off" position, as seen in Figure 5. Spring 21 being of less 25 strength than spring 17, so when the ignition handle is in its off position, stems 13 and 14, will come together as seen in Figure 4. In the form shown in Figure 6, spring 22 may take the place of spring 21, and return the 30 button to its outer, or normal, position upon releasing the pressure thereon. In this form a collar 23 may be applied to the under side of the button to provide space for the compressed spring, and give a position 35 limitation to the movement of the button.

While the ignition handle 9, is away from "off" position, the balls 15, of all the buttons, are in their respective holes in plate 19, and should so remain until the handle 40 9 returns to "off" position. The holes in plate 19 must be so spaced or arranged that none of the balls can fall into the wrong 45 hole. This may be accomplished by limiting the angular play of handle 9, and placing the holes at a greater angular distance from each other, or by putting each hole at a different distance from the center from all the others; I have, however, provided 50 stops 24 for that purpose.

Having thus described my invention, and an embodiment of it, in the full, clear and exact terms required by law, and knowing that it comprises novel, useful and valuable 55 improvements in the art to which it pertains, I here state that I do not wish to be limited to the precise construction and arrangement of the several parts, as herein set forth, as the same may be variously modified by a skilled mechanic without departing from the spirit of the invention.

What I claim and desire to secure by Letters Patent of the United States, is the following, to wit:

1. A permutation lock provided with a 60 rotating shaft and a plurality of plates hav-

ing registering perforations, one of said plates secured to said shaft and rotatable therewith, sectional stems in said perforations, push buttons having stub stems projecting into said perforations and adapted 70 to push those stems into position with their sectional divisions in and out of register with the dividing planes of said plates, thereby controlling the rotation of said rotatable plate. 75

2. A permutation lock having a rotary shaft carrying a disc, buttons provided each with a stud, stems operated by said buttons and adapted to engage said disc, said buttons provided with springs adapted to release said engagement with said disc. 80

3. A permutation lock, comprising a rotating shaft and plates having registering perforations, one of said plates secured to said shaft and rotating therewith, push buttons provided with stub stems projecting into said perforations and having a limited play therein, springs in said perforations, said buttons provided with interchangeable stems engaging the rotatable plate adapted 90 to permit or prevent its rotation and said springs adapted to hold said interchangeable stems in position against said stub stems of said push buttons. 95

4. A permutation lock having a rotary shaft carrying a disc, perforations in said disc, interchangeable stems in said perforations, buttons engaging said stems and a coil spring in each perforation adapted to release said engagement. 100

5. A permutation lock, comprising a perforated rotatable member, buttons provided with studs engaging the perforations in said member interchangeable stems movable in said perforations and means for adjusting the position of said stems with reference to said rotatable member. 105

6. A permutation lock, comprising, a front plate, a middle plate and a back plate, 110 perforations in said plates, a perforated rotatable disc registering with said plates, means to rotate said disc, a locking device for said disc consisting of sectional stems in said perforations, push buttons engaging said stems to operate the same into locking 115 or unlocking position.

7. A permutation lock, comprising a plurality of perforated plates and a rotary shaft carrying a perforated disc, interchangeable stems in said perforations adapted to lock said disc in position, buttons provided with studs adapted to control the movements of said stems and spring means in said perforations adapted to release said locking engagement of said stems. 120 125

8. A permutation lock comprising stationary perforated plates, a rotary shaft carrying a perforated disc registering with said plates, interchangeable stems in said perforations adapted to lock said disc in an 130

inoperated position, buttons provided with studs engaging said stems and controlling their movements and springs in said perforations adapted to release the locking engagement of said stems.

9. A permutation lock comprising, a front plate, a middle plate and a back plate, perforations in said plates, an ignition rotatable shaft fitted in one of said perforations of each plate, a perforated disc carried by said shaft and located between said middle and back plates, means adapted to lock said shaft against rotation, consisting of a series of buttons having each a stem adapted to engage said perforations in said plates and disc, movable sectional stems in said perforations adapted to be operated by said buttons and lock said shaft in an inoperative position.
10. A permutation lock having a front 20 and a back plate, perforations in said plates, an ignition rotatable shaft fitted in one of said perforations of each plate, a perforated disc between said plates, carried by said shaft, means adapted to lock said shaft 25 against rotation consisting of a plurality of interchangeable sectional stems movably mounted in said perforations of said plates and disc, buttons adapted to control the movements of said stems and thereby lock 30 said shaft in an inoperative position and means in said perforations to release said locking engagement.

In testimony that I claim the foregoing I have hereto set my hand this 20th day 35 of November, 1920.

OTTO H. STOLBERG.
